CLAIM

The ornamental design for a combined toy I-beam and block, as shown and described.

DESCRIPTION

FIG. 1 is a front elevational view of a combined toy I-beam and block showing my new design, the rear elevational view being identical;

FIG. 2 is a left side view thereof;

FIG. 3 is a right side view thereof;

FIG. 4 is a top view thereof; and,

FIG. 5 is a bottom view thereof.
